RESUSCITATING DEVICE

Norman H. Stensager, 11032 Harrison Ave. S.,
Minneapolis, Minn. 55431

Filed Mar. 11, 1971, Ser. No. 123,497

Term of patent 14 years

Int. Cl. D24—02

U.S. Cl. D83—1 G

FIG. 1.

FIG. 2.

FIG. 3.

FIG. 4.

FIG. 1 is a top plan view of a resuscitating device embodying my design;

FIG. 2 is an end elevational view thereof;

FIG. 3 is a side elevational view thereof; and

FIG. 4 is a bottom plan view thereof.

An end elevational view taken from the end opposite that shown in FIG. 2 is essentially a mirror image thereof.

A side elevational view taken from the side opposite that shown in FIG. 3 is essentially a mirror image thereof.

I claim:

The ornamental design for a resuscitating device, as shown and described.
